APPARATUS FOR CLAMPING AND ALIGNING PLATES OR THE LIKE

Herbert M. Neuhaus, Santa Monica, Calif.

Application November 29, 1948, Serial No. 62,588

5 Claims. (Cl. 113—99)

(Granted under Title 35, U. S. Code (1952),
sec. 266)

1

The invention described herein may be manufactured and used by or for the Government of the United States of America for governmental purposes without the payment of any royalties thereon or therefor.

This invention relates to apparatus for clamping and aligning plates or the like, and more particularly to apparatus for clamping and aligning or holding plates or the like with edges thereof contiguous and aligned in position to be worked upon, e. g. to be welded, brazed, or otherwise joined.

An object of the invention is to provide apparatus of the class referred to which is of simple and economical construction, and which may be operated effectively by unskilled personnel without special training.

Another object of the invention is to provide apparatus of the character stated including clamping members adapted to be positioned on opposite sides of a pair of aligned plates to bridge the contiguous plate edges, and to be held in contact with corresponding faces of the plates by a tension member connecting the clamping members, the tension member being subjected to cumulative increments of tension by a novel and improved force-applying mechanism. A correlative object is to provide, in such an apparatus, clamping members which are adapted to yield or be deflected under the action of the tension member, and to thus exert a restoring force resulting in the application of continued clamping force independently of the elasticity of the tension member.

Another object of the invention is to provide apparatus of the kind referred to which is so constructed and arranged that the tension member or members may be constituted by discarded or scrap material such as stub ends of welding rods and metal strapping for containers.

Other objects will become apparent from a reading of the following description, the appended claims, and the accompanying drawings, in which:

Figure 1 is a view partly in elevation and partly in section showing apparatus embodying the invention in use for clamping two plates with edges thereof in contiguous spaced relationship;

Figure 2 is a top plan view of the parts shown in Figure 1, drawn on a reduced scale;

Figure 3 is a top plan view of a clamping or bridge device and a tension member included in the apparatus;

Figure 4 is an elevational sectional view of a modified form of clamping mechanism;

2

Figure 5 is an elevational view of a modified form of clamping mechanism, plates acted upon by the clamping mechanism being shown in section;

5 Figure 6 is a top plan view of the tension member shown in Figure 5;

Figure 7 is a view similar to Figure 5 but showing a further modification;

10 Figure 8 is a view similar to Figure 5 but showing a clamping device of modified form especially adapted for holding plates in angular relationship with edges thereof contiguous and parallel;

Figure 9 shows a further modification by means of which plates of differing thicknesses may be clamped with their contiguous edges aligned; and

15 Figure 10 is a perspective view illustrating the application of a plurality of sets of clamping devices to two sheets or plates in position for being welded or otherwise joined or worked upon.

20 Figures 1, 2, and 3 show one preferred form of apparatus embodying the invention as being an accessory or tool adapted for use in aligning and holding in place two similar sheets, slabs, or plates A and B with their contiguous edges mutually aligned and spaced from each other, e. g.,

25 preparatory to the forming of a weld or other joint. In its general nature this form of apparatus includes two clamping members C and D adapted to be placed on opposite sides of the sheets A and B so as to have clamping and abutting engagement with corresponding faces of the plates. A tension member E extends between the contiguous edges of the plates A and B and through openings 1 and 2 in the members C and D; and is adapted to be placed under tension and secured in such condition by a one-way-acting

30 gripper device 3 on the clamping member C and a one-way-acting gripper device 4 on the clamping member D. A force applying element generally designated F is equipped with a one-way-acting

35 gripper 5.

40 Considering the mode of operation generally, the clamping parts C and D are positioned as shown in Figure 1 and the tension member E is anchored in the gripper device 4 of the clamping member D. The member E is extended through the openings 2 and 1 in the clamping members D and C so as to be engageable by the clamping device 5 on the force applying element F. The clamping device 3 is so constructed as to enable the tension member E to move relatively upwardly or away from the clamping device D, but not to move in the opposite direction. The construction of the clamping device 5 is such that it can

45 move downwardly and toward the clamping

50

55

member C freely with respect to the tension member E, but to grip and hold the rod E when the device 5 moves upwardly. When the parts have been so positioned, the force applying element F is operated to build up tension in the member E, thereby causing the clamping members to press firmly against the plates A and B to hold them in position.

The clamping members, the tension member, and the force applying element may be constructed in numerous different forms so as to operate in the general manner set forth above. In the embodiment shown in Figures 1, 2, and 3, the clamping member C is formed as a channel section or open C section including legs 6-6 and a connecting part or bridge 7. The clamping member D similarly includes legs 6-6 and a bridge part 7, together forming an open C section.

The gripping device 4 on the clamping member D comprises a pair of jaws, at least one of which is movable relatively to the other so as to effect a clamping grip on the member E. In the form shown one of the jaws comprises a fixed lug 8 which may be formed integrally with or assembled into the clamping member D. The other jaw comprises a cam 9 pivoted as at 10 on the member D. The cam 9 may be provided with a releasing finger 11 by which the cam may be rocked against the urge of a spring 12 for increasing the opening between the lug 8 and cam 9 to facilitate insertion of the tension member E between the jaws or removal of the member E. The lug 8 and cam 9 may be toothed or roughened to any desired degree to provide for effective gripping of the tension member E, the required roughening of the parts depending upon the characteristics of the material of which the tension member E is formed. The gripper 3 on the clamping member C may comprise parts identical with those described with reference to the gripper 4.

In accordance with one feature of the invention, the tension or force applying element F is constructed and arranged with reference to the parts C, D, and E so as to enable building up by increments of a cumulative clamping force by repeated or intermittent operating movements of the member F. In the form shown, the force applying element F comprises a simple jack-lever having a long handle arm 13, a fulcrum lug 14 adapted to seat in a depression 15 in the clamp C, and a short arm 16. The gripper device 5 is disposed on the short arm 16 and comprises a fixed lug 17, a cam 18 pivoted as at 19, a spring 20 yieldably urging the cam 18 to gripping position, and a releasing finger 21; the general construction and arrangement of these clamping parts being similar to the construction and arrangement of the clamping devices 3 and 4 previously described. The jack-lever F is formed with an opening 22 through which the tension element E can be extended for being grasped by the clamping device 5.

In use, the clamping members C and D are positioned as shown in Figure 1 with the legs 6 engaging corresponding faces of the plates A and B. If desired, the plate-contacting faces of the legs 6 may be roughened to any degree to prevent slipping of the clamping members C and D with respect to the plates. When the clamping members have been positioned as stated above, the tension member is inserted between the fixed lugs and pivoted cams of the grippers 3, 4, and 5, as clearly shown in Figure 1. Intermittent

rocking of the jack-lever F about the fulcrum 14 will result in the application of increasing tension to the member E. Following each application of additional tension, the gripper device 3 will hold the tension member E so as to maintain it under cumulative tension independently of any continued application of force by the jack-lever F. In fact, the lever F and its associated gripping device 5 may be removed from the clamping member C and tension member E after the desired tension has been built up in the member E without relieving the clamping force.

An unusual advantage is obtained by forming the clamping members C and D in the open C or channel shape as previously described. The bridge portions 7 of the clamping members are resilient and unsupported except immediately adjacent the legs 6, so that the bridge portions can be deflected or deformed inwardly toward the plates being clamped when tension is applied to member E. The inwardly deflected bridge members 7 constantly tend to return to their normal or non-deflected positions, and this tendency assures that the legs 6 will maintain constant pressure on the plates A and B even though the tension member E might assume a slightly stretched or elongated set condition.

Figures 1 to 3 show the tension member E as comprising a simple round rod. When the apparatus is used for aligning and holding plates to be welded, short or stub ends of welding rods usually available will serve admirably for use as the tension member E. It will be understood, however, that elongated members of substantially any shape and of sufficiently strong material may be used.

Figure 4 shows a clamping member in which the lug 8 has been replaced by a cam 9. The principle of operation is the same as that described for parts C and D in Figures 1 to 3.

Figures 5 and 6 show a modified clamping apparatus especially adapted for use in clamping and holding plates under such conditions that it is not possible or convenient to apply a clamping member, such as the member D, to one side of, for example, under the plates A and B. In this construction a single C-shaped clamping member C is bridged across the plates A and B on one side, say the upper side thereof, and a special tension member E⁶ is used in place of the simple tension member E previously described. The member E⁶ comprises a shank 23 and a unitarily formed abutment means 24-24 providing a T-shaped element which performs the functions of the two parts E and D shown in Figure 1. The cross part 24-24 of the T-element E⁶ is sufficiently thin to be passed between the contiguous edges of the sheets A and B when disposed parallel of their edges. In use, the cross part 24-24 is first turned at 90° to the position shown in Figure 5, and is then inserted downwardly and turned to the Figure 5 position so as to bridge or span the space between the plates A and B. Thereafter, the clamping device C is applied in the manner previously described; and tension is created in the member E⁶ by suitable means, for example, the jack-lever F previously described.

Figure 7 shows a further modification for use under conditions in which it would not be convenient to insert a C-shaped or T-shaped clamping element on one side of the plates A and B. In this form the tension member E⁷ comprises a shank 25 which is welded or otherwise joined in a unitary way to an abutment, for example as an

I-beam 26, a portion of which is shown in Figure 7.

The modification shown in Figure 8 is especially suited for holding plates A and B at an angle to each other. In this embodiment the upper clamp C⁸ is the same as the clamp C shown in Figure 1 with the exception that the ends of its legs 6-6 are rounded as at 27. The lower clamp D⁸ has legs whose plate-engaging faces 28-28 are formed at an angle to each other corresponding to the angle at which the plates A and B are to be clamped. Clamps such as the clamp D⁸, but formed with plate-engaging faces of different mutual angularity, may be provided according to the nature of the work to be performed. However, a single clamp, such as the clamp C⁸ shown in Figure 8 with the rounded leg ends 27, can cooperate effectively with clamping members D⁸ having their faces 28-28 at different angles. The clamp C⁸ is shown with rounded leg ends. It may also have legs faced to mate with faces 28-28 of clamp D⁸.

Figure 8 illustrates the use of a tension member E for the dual purpose of gauging the space between the contiguous edges of the plates A and B, and cooperating with the clamping members C⁸ and D⁸ for holding the plates in predetermined positions. Tension members of properly selected size may be used similarly for this dual purpose in connection with the apparatus disclosed in the other figures of the drawings.

Figure 9 illustrates how plates A⁹ and B⁹ of different thicknesses may be clamped in aligned position. This may be facilitated by a slight rounding of the edges of the plate-engaging faces of the clamping member C.

In practicing my improved method, the plates to be welded or otherwise joined are placed in substantially abutting relationship and a tension member, e. g. a rod, is extended between the contiguous plate edges and is attached to resilient clamping bridges bearing against opposite faces of the plates. Tension is developed in the rod by restraining lessening of tension while adding increments of tension by applying intermittent force to the rod and the clamping bridges.

In forming a joint between two plates, such as by welding, a plurality of pairs of clamping devices C and D and associated tensioning members E may be positioned at spaced points along the contiguous edges of the sheets as indicated in Figure 10. The jack-lever F may then be successively applied to the pairs of clamping devices and tension members E until all of the clamping devices are held firmly against the plates A and B. The weld may then be formed along the joint and between the pairs of clamping devices, after which the clamping devices are removed and the remaining part of the joint is then finally welded. In some instances, the clamping devices may be removed as welding or joining operation progresses.

The apparatus shown and method described are preferred, but changes may be made without departing from the invention as defined in the claims.

I claim:

1. A clamping device for holding plate members with edges thereof mutually aligned and contiguous, comprising a pair of clamping bridges, each having an elongated, resilient arch terminating at opposite ends in spaced faces for bearing on corresponding surfaces of respective plate members, a tension member for connecting the arches of the bridges between the edges of

the plates to be joined, each bridge also having a fixed lug member and an eccentrically pivoted gripping cam cooperating with the fixed lug member to grip the tension member when it is forced between the lug and the cam to permit the tension member to enter but to prevent movement tending to withdraw the tension member, a jack-lever comprising a lever arm, a fulcrum and gripping members for grasping the tension member, the fulcrum bearing on the resilient arch of one of said bridges, so that intermittent lever action against said bridge pulls the tension member farther and farther through the gripping cam and lug members of said bridge, increasing tension in the tension member, whereby the bridges are clamped firmly against opposite sides of the plate members.

2. A welding accessory for holding metal plates in adjoining relationship during welding operations comprising a rod, bracing means connected to the rod and bearing against one surface of each of the plates, an elongated, resilient bridge having faces at its opposite extremities bearing against the other surface of each of the plates, one-way acting gripping members attached to the bridge and cooperating with the rod to hold the bridge firmly against the other surface of each of the plates, one of said gripping members being eccentrically pivoted on said bridge, and a jack-lever having a fulcrum projection bearing on the bridge and having unidirectional gripping members for gripping the rod, whereby the bridge may be forced into position to exert a strong resilient tension through the rod against said bracing means.

3. Apparatus for clamping plates with edges thereof mutually aligned and contiguous, comprising a tension member adapted to extend between the contiguous edges of said plates; abutment means connected to said tension member and being adapted to bear against corresponding faces of said plates; a bridge spanning said plates and having spaced feet respectively adapted to bear against the other faces of said plates; an intermittently operable element having integral unidirectional gripping members coacting with said tension member for subjecting said tension member to cumulative increments of tension; and one-way gripping members mounted on said bridge for gripping said tension member following each operation of said element to maintain said tension member under the accumulated tension.

4. Apparatus for clamping plates with edges thereof mutually aligned and contiguous, comprising a tension member adapted to extend between the contiguous edges of said plates; abutment means connected to said tension member and being adapted to bear against corresponding faces of said plates; a bridge spanning said plates and having spaced feet respectively adapted to bear against the opposite faces of said plates; tension applying means for pulling on said tension member in a direction away from said abutment means to create tension in said member between said abutment means and said bridge; and a pair of jaws on said bridge and between which said tension member extends, at least one of said jaws comprising a cam movably mounted on said bridge and so related to the other of said jaws as to enable the tension member to move through said jaws toward said tension applying means but not reversely.

5. Apparatus for clamping plates with edges thereof mutually aligned and contiguous, com-

prising a tension member adapted to extend between the contiguous edges of said plates; a first bridge spanning said plates and having spaced feet, respectively adapted to bear against corresponding faces of said plates; one-way gripping members, secured to said first bridge for securing the tension member thereto; a second bridge spanning said plates and having spaced feet, respectively adapted to bear against the other faces of said plates; tension applying lever means having unidirectional gripping members and positioned on said second bridge for pulling on said tension member in a direction away from said first bridge to create tension in said member between said first bridge and said second bridge; 15 and a gripping device on said second bridge engageable with said tension member for maintain-

ing the latter under the tension created by said tension applying means.

HERBERT M. NEUHAUS.
